UNITED STATES PATENT OFFICE.

WILLIAM C. KISNER, OF WATSON, WEST VIRGINIA.

WRENCH.

Application filed November 26, 1923. Serial No. 676,952.

To all whom it may concern:

Be it known that I, WILLIAM C. KISNER, a citizen of the United States of America, and resident of Watson, county of Marion, 5 and State of West Virginia, have invented certain new and useful Improvements in Wrenches, of which the following is a specification.

This invention relates broadly to adjustable wrenches, and more specifically to a wrench of the well known type in which one jaw, formed integral with and disposed at substantially a right angle to a toothed rack bar, is adjustable relative to the other 15 jaw by rotation of a knurled worm disposed in cooperative relation to said rack bar.

The primary object of the invention is to provide a wrench of the type mentioned which has a construction adapting it for 20 use in the manner of a ratchet wrench—that is to say, which may be rotated or swung rearward for obtaining a new hold, following forward movement, without wholly withdrawing or disengaging its jaws from 25 the nut or other object upon which it operates.

A further object is to provide a wrench of the character referred to which firmly 30 grips the engaged nut during forward, or advancing, movement of the latter, and which, when moved rearward, automatically releases the nut to the extent that its jaws freely ride over the latter.

With these and other objects in view, the 35 invention resides in the features of construction which will hereinafter be fully described, reference being had to the accompanying drawings, in which—

Figure 1 is a side elevation of a wrench 40 embodying the invention; and—

Figure 2 is a fragmentary detail section of the same.

Referring to said drawings, 1 indicates generally a head portion, 2 an integral shank 45 or handle, 3 an adjustable jaw, 4 a rack bar formed integral with and disposed at substantially a right angle to said jaw 3, 5 a transverse passageway in said head and in which said rack bar is longitudinally movable for positioning said jaw 3, and 6 a knurled worm operatively engaged with said rack bar, all of said parts, excepting said jaw 3, being of the usual forms and constituting parts of an adjustable wrench of 50 a common type.

Disposed in opposing relation to the ad-

justable jaw 3 is a jaw 7 which is shiftable relative to said jaw 3, having an integral rearwardly extending tongue 8 which is mounted for sliding movement in a channel 60 or chamber 9 provided therefor in the wrench head 1, said chamber as herein shown being disposed in a common plane with the passageway 5 and joining the inner end of the latter.

The tongue 8 carries on its rear end an integral rearwardly and inwardly inclined arm or shank 10 which is slidably received within a correspondingly inclined socket 11 provided therefor in the wrench head 1. 70 A slot 12 inclined so as to lie substantially parallel to the plane of the axis of said shank 10 is provided in the tongue 8, and extending through said slot is a pin 13 which has its opposite ends mounted in the opposite walls of the head adjacent to the outer or forward end of said chamber 9, as shown. The shank 10 and the pin 13 cooperate, respectively, with the socket 11 and the slot 12 for guiding movements of the jaw 7 as 80 the latter is shifted to and from cooperative nut-gripping relation to the adjustable jaw 3.

In practice, having first positioned the 85 jaw 7 in its retracted operative position shown in full lines in Figs. 1 and 2, the jaw 3 is adjusted relative thereto by rotation of the worm 6 for fitting said jaws to the nut or other object which is to be rotated by means of the wrench. The wrench is 90 then applied to the nut in such position that rotating movement of the wrench in the direction indicated by the arrow in Fig. 1 will effect turning of the nut in the desired direction. Rearward or return movement of 95 the wrench without disengaging the latter from the nut acts through the nut to slide the jaw outward with respect to the wrench head 1 and away from the jaw 3, as indicated in broken lines in Fig. 1, the jaw-separation being due to the inclination of the direction of movement with respect to the plane of the face of the jaw 3. The distance of the jaw-separating movement described is such that the jaws will ride over the sides 100 of the nut freely and without actuating reverse rotation of the latter.

At the rearwardly swung position of the wrench at which a new hold upon the nut is to be taken, endwise pressure is applied 110 to the wrench through its handle 2 for effecting the return of the jaw 7 to its oper-

ative position in which it cooperates with the jaw 3 for closely gripping opposite sides of the nut. This return shifting movement is produced by pressure of the nut 5 against the outer edge of a transversely disposed arm 14, preferably of the tapered form shown, which is carried by the tongue 8 and which has its outer end received within a relatively larger transverse bore or passage 10 15 provided in the adjustable jaw 3 rearward of the nut engaging face of the latter.

It will be obvious that various minor changes in the forms of some of the parts of the wrench described may be made without departure from the spirit or scope of 15 the invention as defined in the appended claims.

What is claimed is—

1. A wrench comprising a head portion 20 having a transverse passageway therein, a jaw having an integral rack-bar disposed in said passageway, a worm engaged with said rack-bar and rotatable to effect adjustment of the position of said jaw, and a jaw carried by said head in opposing relation to said adjustable jaw and slideable to and from cooperative relation to the latter in a direction inclined relative to the plane of its nut-engaging face.

2. A wrench comprising a head portion having a transverse passageway therein, a jaw having an integral rack-bar disposed in said passageway, a worm engaged with said rack-bar and rotatable to effect adjustment 35 of the position of said jaw, and a second jaw carried by said head portion and slideable to and from cooperative nut-engaging relation to said adjustable jaw, said second jaw being adapted to remain stationary in 40 said relation when the wrench is rotated in one direction and to slide to nut-releasing position when reverse rotation is imparted to said wrench.

3. A wrench comprising a head portion, 45 a jaw carried by said head portion and adjustable in a direction transverse to the latter, said portion having a recess therein, a second jaw disposed in opposing relation to said adjustable jaw and having a tongue 50 slideable in said recess, means cooperating to guide outward and inward sliding movements of said tongue in directions at an angle to the axis of a nut interposed between said jaws whereby said second jaw is main-

tained in closely cooperating relation to said adjustable jaw during forward rotation of such nut and is actuated by rearward rotation of the wrench to move to nut-releasing position.

4. A wrench comprising a head portion, 60 a jaw carried by said head portion and adjustable in a direction transverse to the latter, said portion having a recess therein, a second jaw disposed in opposing relation to said adjustable jaw and having a tongue disposed in said recess, said second jaw being slideable to and from cooperative nut-gripping relation to said adjustable jaw, said head portion and said tongue being provided with cooperating guiding means 65 whereby said second jaw is actuated to move outward in a direction inclined with respect to the plane of the nut-engaging face of the latter by rearward rotation of the wrench when in engagement with a nut interposed 70 between said jaws, and a laterally disposed arm carried by said tongue.

5. A wrench comprising a head portion, a jaw carried by said head portion and adjustable in a direction transverse to the latter, said jaw having a passage therethrough rearward of its nut-engaging face, said head portion having a recess therein, a second jaw disposed in opposing relation to said adjustable jaw and having a tongue received in said recess, said tongue being adapted for sliding movement for carrying said second jaw into and out of cooperative nut-gripping relation to said second jaw in directions inclined with respect to the plane of the axis of a nut acted upon, whereby said second jaw is maintained in seated relation to such nut during forward rotation of the wrench and is actuated to move to nut-releasing position by rearward rotation of the wrench, and an arm carried by 85 said second jaw rearward of its nut-engaging face and adapted to be engaged by such nut for returning said second jaw to its operative position, the free end of said arm 90 being received within the passage of the adjustable jaw.

In testimony whereof, I affix my signature in presence of two subscribing witnesses.

WILLIAM C. KISNER.
